C. P. MOORE

PAPER PUNCH

Filed May 19, 1927

Inventor:
Clarence P. Moore.
by Watson E. Coleman.
Attorney.

UNITED STATES PATENT OFFICE.

CLARENCE P. MOORE, OF PHILADELPHIA, PENNSYLVANIA.

PAPER PUNCH.

Application filed May 19, 1927. Serial No. 192,683.

This invention relates to paper punches and more particularly to a device for punching sheets or cards to enable application thereof to binders and the like.

5 An important object of the invention is to provide a device of this character in which the dies and punches are readily interchangeable to permit variation of the type of opening formed in the paper.

10 A further object of the invention is to produce a device of this character which is adapted to form a plurality of openings in a sheet, but which may be very readily adjusted to adapt the same for use in punching a 15 single opening in the sheet or to vary the space between the openings which are formed.

These and other objects I attain by the 20 construction shown in the accompanying drawings, wherein for the purpose of illustration is shown a preferred embodiment of my invention and wherein:—

25 Figure 1 is a vertical sectional view through a paper punch constructed in accordance with my invention taken on the line 1—1 of Figure 2;

Figure 2 is a plan view of the paper punch with the operating handle removed;

Figure 3 is a front elevation thereof;

30 Figure 4 is a detail view showing the combined tie and punch holders positioned to change the dies;

Figure 5 is a side elevation partially in section of the punch holder with the punch 35 in position therein;

Figure 6 is a rear elevation of one type of punch;

Figure 7 is a bottom plan view of the punch holder;

40 Figure 8 is a detail side elevation of one of the punch and tie holders removed illustrating the adjustability of the paper stops carried by these elements;

Figure 9 is an enlarged plan view of a die;

45 Figure 10 is a vertical sectional view through the die.

Referring now more particularly to the drawings, the numeral 10 generally designates a base to receive the paper to be punched, the rear portion of which is downwardly offset, as indicated at 11, and adapted for attachment to a suitable support 12. The paper receiving base 10 has along one margin thereof a side stop 13 for the paper

and adjacent the downward offset is provided with a gauge rule 14 which extends transversely thereof.

Extending upwardly from opposite sides of the downwardly offset portion are standards 15, the upper ends of which are provided with openings 16 for the reception of the pivots 17, which pass through ears 18 of an operating handle 19 embodying a transversely extending bar 20, to the ends of which the ears 18 are connected. Below the pivots 17, the standards receive the ends of a stationary shaft 21 having mounted thereon arms 22 having clamping engagement with the shaft, as at 23, so that they may be secured in longitudinally adjusted positions 70 thereon. The outer end of each arm 22 is provided with a transversely extending head, generally designated at 24, having its lower surface 25 adapted to flatly abut the upper surface of the downwardly offset portion 11 in one position of the shaft and thus limit rotative movement of the arms about the shaft in this direction. Each head has in what is its front face when in said position a transversely extending slot 26, the lower wall of which is coplanar with the upper portion of the paper receiving base when the head is in such position and this slot is of sufficient width to permit insertion of a paper pile of the desired thickness. The head above and below the slot 26 is provided with vertically aligned bores 27 and 28 and the bore 27 has communicating therewith a vertically extending slot 29 formed in the head and terminating short of the lower end of that portion of the head lying above the slot.

Slidable in the bores 27 are punch holders 28^a, each having in its lower end a bore 29^a, for the reception of the shank of a punch 30. The bottom surface of each punch holder is formed with a slot 31 radial to the bore 29^a and adapted to receive the upper end of the flange 32 of a keyhole punch. Each punch is held in position by a setscrew 33, the outer end of which operates in the slot 29 and prevents rotation of the punch and punch holder. This set-screw further serves to prevent dislodgment of a spring 34, which surrounds the upper ends of the punch holders 28^a and has its upper end engaged with a transversely extending pin 35 carried thereby when the punch holders are removed.

from the bores 27. The upper ends of the punch holders are rounded, as at 36, for engagement with the bar 20 of the handle.

The lower ends of the bores 28 are enlarged, as at 37, to receive the flanges 38 of dies 39, which will, of course, correspond in character to the punch 30 which is being employed. The die illustrated in Figures 9 and 10 is of that type adapted for use in connection with keyhole punches and has a central aperture 40 for the passage of the body of the die and a radial slot 41 for the passage of the web thereof. These dies are held in position by set-screws 42 extending through what are the rear faces of the heads when in normal position. It will be obvious that these set-screws will be readily accessible when the arm 22 is bodily rotated, so that the head lies to the opposite side of the shaft from that which it normally occupies, as illustrated in Figure 4, so that these dies may be removed and replaced.

Each arm 22 has adjustably mounted thereon a slotted bar 43 having at its forward end a depending finger 44, which bridges the slot 26 and forms a stop for the edge of the paper. As shown in Figure 4, the upper ends of the punch holders will clear the bar 20 in one position thereof, so that the rotation of the arms necessary to render the set-screws 42 accessible may be accomplished by simply loosening the securing elements of the clamps.

Since the construction hereinbefore set forth is capable of a certain range of change and modification without materially departing from the spirit of the invention, I do not limit myself to such specific structure except as hereinafter claimed.

40 I claim:

1. In a paper punch and in combination, a base having the rear portion thereof downwardly offset, standards arising from opposite ends of the downwardly offset portion, a shaft mounted in said standards, arms adjustably secured to said shaft and each having at its outer end a transversely

extending head which flatly abuts the upper surface of the downwardly offset portion, said heads having slots formed in the forward faces thereof the bottom walls of which are co-planar with the upper surface of the higher portion of the base, the head at opposite sides of the slot having vertically aligned bores for the reception of a punch holder and a die, a handle pivoted to the standards having a portion for engagement with the punch holders mounted in said heads, each punch holder having a bore in its lower end for the reception of the shank of a punch, the bore of the head within which the punch holder operates having a slot and a securing element extending through the wall of the punch holder for engagement with the shank of a die having its end extended for engagement in the slot of the head to thereby hold the die and die holder against rotative movement with relation to the head.

2. In a paper punch and in combination, 70 a base having the rear portion thereof downwardly offset, standards arising from opposite ends of the downwardly offset portion, a shaft mounted in said standards, arms adjustably secured to said shaft and each having at its outer end a transversely extending head which flatly abuts the upper surface of the downwardly offset portion, said heads having slots formed in the forward faces thereof the bottom walls of which are co-planar with the upper surface of the higher portion of the base, the head at opposite sides of the slot having vertically aligned bores for the reception of a punch holder and a die and a handle pivoted to 75 the standards having a portion for engagement with the punch holders mounted in said heads, said portion of the handle in one position thereof permitting rotation of the arms about the shaft to invert said heads.

In testimony whereof I hereunto affix my signature.

CLARENCE P. MOORE.
